UNITED STATES PATENT OFFICE.

LEWIS GIBBS, OF CANTON, OHIO.

DESIGN FOR A LAWN-RAKE.

SPECIFICATION forming part of Design No. 25,956, dated August 18, 1896.

Application filed March 15, 1895. Serial No. 541,941. Term of patent 14 years.

To all whom it may concern:

Be it known that I, LEWIS GIBBS, a citizen of the United States, and a resident of Canton, county of Stark, State of Ohio, have invented a new and useful Design for Lawn-Rakes, of which the following is a full, clear, and exact description, reference being had to the accompanying drawings, making part of this specification.

10 My invention relates to a design for lawn-rakes.

In the accompanying drawing I have illustrated the design in perspective.

15 My design consists of and the leading features are a longitudinal bar A, composed of parallel upper and lower sides B and C and

a round or curved back side D. Projecting from the bar are a series of U-shaped teeth curved transverse the bar.

E denotes a tubular extension connected with the bar. F denotes a handle extending from said tubular extension.

What I claim is—

The design for lawn-rakes, as herein shown and described.

In testimony whereof I have hereunto set my hand this 17th day of February, A. D. 1895.

LEWIS GIBBS.
